UNITED STATES PATENT OFFICE.

LEWIS M. RADER AND DAVID S. GOULD, OF KENT, WASHINGTON.

COOLER OR REFRIGERATOR.

1,258,457.

Specification of Letters Patent.

Patented Mar. 5, 1918.

Application filed February 12, 1916. Serial No. 77,890.

To all whom it may concern:

Be it known that we, LEWIS M. RADER and DAVID S. GOULD, citizens of the United States, residing at Kent, in the county of King and State of Washington, have invented new and useful Improvements in Coolers or Refrigerators, of which the following is a specification.

This invention relates to a cooler or refrigerator for domestic and other uses, the object of the invention being to provide a cooler which is adapted to be arranged in the line of a water service pipe within a house or other building, so that in the circulation of the water through the pipes, when water is drawn from the faucets, the cold water passing through the cooler or refrigerator will maintain a low temperature therein for the preservation of contained perishable substances.

A further object of the invention is to provide a cooler or refrigerator which is simple of construction, inexpensive of installation and use, which provides for the cooling action of the water in an efficient manner, which provides also for free ventilation of the interior compartments containing the substances to be cooled, and which dispenses with the necessity of employing ice as a refrigerant or cooling medium.

The invention consists of the features of construction, combination and arrangement of parts hereinafter fully described and claimed, reference being had to the accompanying drawing in which:

Figure 1 is a front elevation of a cooler or refrigerator embodying our invention, and showing the same arranged between sections of a water conducting pipe.

Fig. 2 is a vertical longitudinal section through the device.

Fig. 3 is a sectional plan view on the line 3-3 of Fig. 1.

In carrying our invention into practice we provide a cooler or refrigerator comprising a preferably cylindrical outer casing 1, which is vertically disposed and provided with top and bottom head portions 2 and 3 constructed and arranged to form a water tight receptacle. Arranged within this outer casing 1 is a similarly shaped, but smaller, inner cylindrical casing 4 provided with top and bottom heads 5 and 6 also constructed and applied to form a water tight receptacle. The two receptacles are concentrically arranged and the inner receptacle is spaced at all sides from the outer receptacle to provide a water containing jacket or chamber 7.

The casing 1 is arranged between sections 8 and 9 of a water service pipe of a house or other building leading from the main to discharge faucets, and is provided with inlet and outlet connections 10 and 11 communicating with the said pipe sections 8 and 9, respectively. The inlet connection 10 is located at one side of the casing 1, in proximity to the bottom thereof, while the outer connection 11 is arranged at the diametrically opposite side of said casing and adjacent to the top thereof, so that the cold water entering said casing will flow first into the bottom of the chamber 7 and upwardly to the top of said chamber before discharge. The outlet 11 is arranged substantially at the level of the discharge pipe section 9, so that in the use of the device it will be understood that the water chamber or jacket 7 will at all times be filled with a cool body of water up to the level of the outlet 11, thus keeping the inner casing 4, which will be entirely surrounded by said body of water, at a low temperature.

The casing 4 is provided with a series of shelves, trays or other suitable supports 12 on which the substances to be kept cool, or dishes or other receptacles containing the same, may be placed, and at its front the casing 4 is provided with a doorway or opening 13 which registers with a doorway or opening 14 in the front of the outer casing 1, a flange or partition 15 extending between the margins of said doorways or openings, forming a water tight connection 95 whereby the doorways are separated from the water space, allowing free and ready access to the interior of the inner casing at all times. For the purpose of securing free ventilation of cold air within the inner casing, said casing is provided at its lower end with an air inlet pipe or tube 16 and at its upper end with an air outlet or exhaust tube or pipe 17, whereby the interior of the inner casing will at all times be kept dry 100 and provision made for carrying off all odors from the food or other substances contained therein.

In the use of the device, it will be understood that it may be arranged within a kitchen or pantry of a house, or in a suitable portion of a store, in the line of con-

nection between sections of a cold water supply pipe leading to faucets from which water is periodically drawn, by means of which the cooling effect of the water will be utilized for a refrigerating action without cost in this connection, the circulation of the water causing a constant changing of the body of water within the cooler by means of which the heat contained within the inner 5 casing will be abstracted and carried off, thus maintaining said inner casing at a low temperature at all times. By the construction described a simple, inexpensive and economical type of refrigerator or cooler is 10 provided for household or other use, which entirely dispenses with the use of ice, and which in many cases may be employed in 15 place of the ordinary refrigerator.

We claim:—

20 A device of the class described, comprising an outer casing, an inner casing spaced from the outer casing in a vertical direction, said space forming a water jacket that partially surrounds the inner casing, inlet and

outlet pipes to permit water to circulate in 25 the jacket and abstract heat from the interior and contents of the inner casing, a tubular spacing element between the upper walls of the two casings and another element between the bottom walls, openings in 30 each of the walls of the casing to register with the openings in the tubular spacing elements, said elements serving as a ventilating means to provide for changes of air within the inner casing, an opening having 35 a door giving access to the inner casing, and means surrounding the opening and between the two casings to prevent the water from leaving the jacket except at its proper outlet.

In testimony whereof we affix our signatures in presence of two witnesses.

LEWIS M. RADER.
DAVID S. GOULD.
